UNITED STATES PATENT OFFICE.

LORNE A. GRIFFIN, OF EVANSTON, ILLINOIS, ASSIGNOR TO AMERICAN STEAM CONVEYOR CORPORATION, OF CHICAGO, ILLINOIS, A CORPORATION OF NEW YORK.

ASH-CONVEYER.

1,331,987.

Specification of Letters Patent. Patented Feb. 24, 1920.

Application filed August 4, 1919. Serial No. 315,291.

To all whom it may concern:

Be it known that I, LORNE A. GRIFFIN, a citizen of the United States, residing at Evanston, in the county of Cook and State 5 of Illinois, have invented a certain new and useful Improvement in Ash-Conveyers, of which the following is a full, clear, concise, and exact description, reference being had to the accompanying drawings, forming a 10 part of this specification.

My invention relates to ash conveyers, and more particularly to the construction of the conduit forming a part of an ash conveyer system. The present invention 15 has for its object the provision of an ash conveyer comprising a conduit, the several constituent elements of which are so conformed, arranged and supported that anyone of the same may be removed for inspection, 20 replacement or repair with the utmost facility, and without making it necessary to provide elaborate or special devices for supporting the conduit elements other than the one which it is necessary to remove.

25 In ash conveyer conduits as heretofore constructed, the removal of one or more elements of the conduit removes the support of one or more of the elements of the conduit which are not removed, so that it 30 has been necessary to provide elaborate and special devices for temporarily supporting the conduit structure when one or more elements were removed. This difficulty has 35 been particularly serious when it has become necessary to remove a conduit element forming a part of a vertical run of such a conduit.

These and other features of my invention are fully set forth in the following description 40 wherein reference is made to the accompanying drawings, in which—

Figure 1 is a vertical sectional view illustrating portions of horizontal and vertical runs of an ash conveyer conduit, together 45 with a sectional right angle elbow affording communication between the same.

Fig. 2 is a fragmentary elevational view illustrating a modification of the arrangement shown in Fig. 1.

50 Fig. 3 is a view similar to Fig. 1 illustrating a conduit wherein the sections of which the horizontal and vertical runs are formed are semi-cylindrical in shape.

Fig. 4 is a fragmentary elevational view

illustrating a modification of the arrangement shown in Fig. 3.

Fig. 5 illustrates the application of my invention to an arrangement wherein the vertical portion or riser of the conduit comprises two separate passages, and

Fig. 6 is a horizontal sectional view taken on the line 6—6 of Fig. 5 and looking in the direction indicated by the arrows.

Referring first to Fig. 1, the reference numerals 10 and 11 respectively indicate 65 vertical and horizontal portions of a conveyer conduit which are connected by a right angle elbow 12. It will be understood that that part of the horizontal portion of the conduit which has not been shown leads 70 from the boilers or other point from which the ashes are to be conveyed and is provided with suitable hoppers for introducing the ashes into the conduit. It will also be understood that the vertical portion of the 75 conduit leads off to an ash tank, or to any point where the ashes are to be deposited. Furthermore, if the system is of the steam jet type, the conduit at one or more points is provided with a nozzle for discharging 80 steam under pressure into the conduit in the direction of travel of the ashes to carry the latter through the conveyer. Since my present invention is concerned solely with the construction and arrangement of the 85 several parts of the conduit, I have not deemed it necessary to illustrate the hoppers, ash tank and steam jets in the figure now under consideration.

The vertical portion of the conduit illustrated at 10 comprises a plurality of sections, *a*, *b*, *c*, etc., and *a—a*, *b—b*, *c—c*, etc. The elbow 12 comprises the curved section *x* and the bottom and end sections designated as *y* and *z* respectively, the several 95 abutting edges of said elbow sections being connected together by bolts 13 coöperating with apertured lugs 14.

Attention is directed to the fact that each of the sections *a*, *b*, etc., and *a—a*, *b—b*, etc., of which the vertical run of the conduit consists, comprise two portions one of which has a circumference of a little more than 180°, the other portion being a little less than 180° in circumference. Therefore, 100 in elevation, these pipe sections appear to be substantially L-shaped.

It will be noted that the upper portion of

the curved elbow section z and the intermediate shoulders of the elbow section z are conformed to coöperate with the lower end of the vertically disposed section a , 5 the upper portion of the elbow section z coöperating with the lower portion of the section $a-a$ to provide a cylindrical passage up as far as the intermediate shoulders of the section a . The upper half of the 10 elbow section z lies flush with the intermediate shoulders of the section a , and thus provides an annular surface to receive the lower portion of the section $a-a$ which coöperates with the upper portion of the section 15 a to continue the cylindrical passage up as far as the upper end of the section a . The section b resting upon the annular support afforded by the upper end of the section a and the intermediate shoulders of the 20 section $a-a$ continues the cylindrical passage up as far as the upper end of the section $a-a$. The cylindrical passage is continued upwardly by L-shaped sections $b-b$, $c-c$, etc., all coöperating in the manner 25 just described.

It will be noted that no one of the several sections of the cylindrical portion of the conduit depends solely upon any other section for its support. Thus, for instance, 30 section a is supported by the elbow section z and by the intermediate shoulders of the elbow section z . Similarly, conduit section $a-a$ is supported by the upper end of the elbow section z and by the intermediate 35 shoulders of the section a . All of the other sections of the vertical portion of the conduit are similarly supported, no one depending solely upon any other section for its support.

40 So far as my present invention is concerned, the horizontal run of the conduit may be formed in any suitable manner. It may consist of whole pipe sections as shown, it may be made up of L-shaped sections 45 similarly to the vertical portion of the conduit, or it may be formed of plain semi-cylindrical sections bolted or otherwise suitably secured together.

Tight joints between the abutting end 50 and longitudinal edges of the several conduit sections are provided by any suitable form of packing. For the purpose of illustration I have illustrated a grouting material placed between the abutting edges of 55 the pipe sections. This grouting material is desirably, but of course not necessarily, of the kind described and claimed in patent to James A. Daviess No. 1,278,869, and of course it will be understood that I contemplate scoring any of the grouted joints as 60 described in the Daviess patent if that should be necessary or desirable.

The grouted or other suitably packed joints between the ends of the conduit sections and the surfaces adjacent thereto are

protected by semi-circular bands 15-15, the bands of each pair being secured together by suitable bolts 16-16 as illustrated. These bands serve to retain the grouting or other packing material in position, and also serve to retain the several conduit sections in proper relation to each other.

With the arrangement herein shown, any section of the vertical portion of the conduit 75 may be removed without withdrawing support from any of the other sections. For instance, assume that section b is to be removed for inspection, replacement or repair. All that need be done is to clamp the 80 bands e and f in the positions shown in dotted lines, remove the band d and loosen the grouting or packing material adjacent the edges of the section b . Section b may then be removed without disturbing the 85 relation of the other elements, since the section $a-a$ which rests on the top of the elbow section z and the section a now carries the weight of all of the sections which lie 90 above the removed section b .

The modified construction illustrated in Fig. 2 is substantially like that shown in Fig. 1, and similar reference characters have been applied to corresponding parts. The arrangement shown in Fig. 2 differs from that shown in Fig. 1 in that the several sections constituting the vertical portion of the conduit are provided with lugs 17-17 which are secured together with bolts 18 to provide a slightly more rigid structure. 95 The several semi-cylindrical clamping bands 15 in this construction serve merely to hold the grout which is put in place between the opposing ends of the adjacent sections in position. In removing one of the L-shaped sections of this arrangement, it is necessary only that the three clamping bands associated with that section be removed. The four bolts, two on each side of the conduit, 100 are then removed and the section taken out 110 of the conduit for repairs or replacement.

In the modified arrangement shown in Fig. 3, the several pipe sections of which the conduit is formed are made semi-cylindrical and are secured to one another by the several clamping bands shown at 15-15. The elbow 20 affording communication between horizontal conduit 21 and the vertical conduit 22 is preferably made of several sections as illustrated, which are clamped or secured together by the lugs and bolts shown at 23-23. Grout is interposed between the longitudinal edges 24 and between the opposing ends 25 of the several sections, as is the case in the structure shown in Fig. 1. 115 In this construction the horizontal part of the conduit is preferably made up of units or sections which are identical with those which constitute the vertical conduit. If one of the sections, as for example the sec- 120 125 130

tion shown at *g*, is to be removed, the clamping bands *h* and *i* are moved to the positions indicated by the dotted lines and securely clamped around the conduit. The 5 clamping band *j* is then removed from the conduit and the grout interposed between the section *g* and the adjacent sections removed. The section *g* may then be removed laterally and repaired or replaced by a new 10 section. Similarly, any one or more of the sections constituting the horizontal run of the conduit may be removed and replaced.

The arrangement shown in Fig. 4 is similar to that shown in Fig. 3, except that each 15 of the several semi-cylindrical sections is provided with a plurality of lugs through which the bolts 26 pass for the purpose of attaching the several sections to adjacent sections. The clamping bands 15 in this arrangement serve merely to hold the grout or 20 filler in place between adjacent ends of the pipe sections. In removing one of the semi-cylindrical pipe sections employed in this construction, the clamping bands 15 associated 25 with the section to be removed are disconnected from the conduit, and the bolts 26 holding that particular section removed. The section may then be removed as shown in this figure.

30 In all of the foregoing arrangements the vertically extending conduit comprises a plurality of pipe sections or units which cooperate to form a single continuous passageway or conduit, but I may arrange the several sections to form two or more conduits positioned immediately adjacent one another and each serving to support the other. In 35 Figs. 5 and 6 I have shown such an arrangement. In these figures 27 designates the horizontal run of pipe and 28 and 29 are vertical runs which communicate with the horizontal conduit as shown. A gate 30 pivoted at 31 and operated by weighted 40 lever 32 is employed for the purpose of affording communication between the horizontal conduit and either one of the vertical conduits 28 and 29.

In this arrangement the several sections 45 which make up the vertical pipe sections 28 and 29 may be either whole sections as illustrated in these figures, or semi-cylindrical sections as shown in Figs. 1 to 4 inclusive. Each semi-cylindrical section is provided 50 with two or more lugs 33-33, which cooperate with the bolts 34-34 for the purpose of locking the several sections of different conduits to one another. If it is found necessary or desirable to remove one 55 of the sections in this construction, as for example, the section shown at *k*, the two clamping bands fitting over the ends of this section are removed, as are the bolts co-operating with this particular section. The 60 grout interposed between the section *k* and the adjacent sections is then removed and

the section moved laterally out of the conduit.

In the use of this construction, the operation of the conveyer system need not be discontinued during the repair or replacement 70 of any one of the sections forming a part of either one of the vertical conduits 28 and 29. For example, when the section *k* is removed, the gate 30 is moved to the dotted line position so that it discontinues communication between the horizontal conduit 75 27 and the vertical conduit 29. A steam nozzle shown opposite the conduit 28 is then put in operation and the conduit 28 employed for transporting the ashes. 80

From the above description it will be observed that I provide a vertical conduit made up of several sections, the sections being disposed in two or more vertical rows, the sections of one row being connected with 85 sections of a second row, whereby any section may be removed from any row without the necessity of providing some auxiliary support for holding the sections above that removed. The several arrangements shown 90 in the accompanying drawings are self-supporting, and continue to be so even though any one of the sections forming part of the vertical conduit is removed.

Having thus described my invention, 95 what I claim as new and desire to secure by Letters Patent of the United States is:

1. A self-supporting vertical conduit for ash conveyers comprising a plurality of sections arranged in two vertical rows and 100 means for connecting the sections of different rows whereby a section of one of said rows may be removed.

2. A self-supporting vertical conduit for ash conveyers comprising a plurality of 105 pipe sections placed end to end to form a continuous passageway, said sections being arranged in a plurality of vertical rows, and means for supporting the several pipe sections of one row from the several sections of 110 a different row, whereby a section of one of said rows may be removed.

3. A self-supporting vertical conduit for ash conveyers comprising a plurality of substantially semi-cylindrical pipe sections arranged in two vertical rows and forming a continuous conduit, and means for supporting the sections of one row from the sections of the other row, whereby one of 115 said sections may be removed. 120

4. A self-supporting vertical conduit for ash conveyers comprising a plurality of substantially semi-cylindrical pipe sections arranged in two vertical rows and forming a continuous conduit, the sections of one row being staggered with respect to the sections of the other row, and means for supporting the sections of one row from the sections of the other row, whereby any one of the sections from either row may be removed. 125 130

- 4
5. A self-supporting vertical conduit for ash conveyers comprising a plurality of substantially semi-cylindrical pipe sections arranged in two vertical rows and forming a continuous conduit, the sections of one row being staggered with respect to the sections of the other row, lugs carried by the sections and bolts extending through said lugs and connecting sections of different rows, whereby any section of either of said rows may be removed.
6. A self-supporting vertical conduit for ash conveyers comprising a plurality of substantially semi-cylindrical L-shaped pipe sections arranged in two vertical rows and forming a continuous conduit, the sections of one row being staggered with respect to the sections of the other row, and means for supporting the sections of one row from the sections of the other row, whereby any one of the sections of either row may be removed for repairs.
7. A self-supporting vertical conduit for ash conveyers comprising a plurality of substantially semi-cylindrical L-shaped pipe sections arranged in two vertical rows and forming a continuous conduit, the sections of one row being staggered with respect to the sections of the other row, lugs carried by the sections and bolts extending through said lugs for supporting the sections of one row from the sections of the other row, whereby any one of the sections of either row may be removed.
8. A self-supporting vertical conduit for ash conveyers made up of a plurality of sections in staggered arrangement whereby any of the sections may be removed for repairs.
9. A self-supporting vertical conduit for ash conveyers comprising a plurality of substantially semi-cylindrical pipe sections arranged in two vertical rows and forming a continuous conduit, the sections of the two rows being in staggered relation, and means for supporting the sections of one row from the sections of the other row, and for preventing collapse of one row upon removal of a section from the other row.

In witness whereof, I hereunto subscribe my name this 30th day of July, 1919.

LORNE A. GRIFFIN.
